CLAIM

The ornamental design for a signal relay device, as shown and described.

DESCRIPTION

FIG. 1 is a front perspective view of the front, left, and bottom sides of signal relay device showing our new design; FIG. 2 is a rear perspective view of the rear, right, and top sides;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown represent unclaimed subject matter of the signal relay device and form no part of the claimed design.
